[57] CLAIM

The ornamental design for a combined bottle and wooden cap for cosmetic products, as shown and described.

DESCRIPTION

FIG. 1 is a front, left perspective view of a combined bottle and wooden cap for cosmetic products showing my new design;

FIG. 2 is a top view thereof;

FIG. 3 is a right side view thereof;

FIG. 4 is a front view thereof;

FIG. 5 is a left side view thereof; and,

FIG. 6 is a bottom view thereof.

The rear of the combined bottle and wooden cap for cosmetic products that is not shown in the drawings does not form part of the claimed design.
